(57) CLAIM

The ornamental design for an armoire, as shown and described.

DESCRIPTION

FIG. 1 is a front perspective view of a armoire showing my new design;

FIG. 2 is a side view, the opposite side view being a mirror image thereof thereof; and,

FIG. 3 is a front view.

The broken lines showing the drawer and door hardware and the feet on the armoire are for illustrative purposes only and form no part of the claimed design.

1 Claim, 3 Drawing Sheets

FIG. 1

FIG. 3
